UNITED STATES PATENT OFFICE.

GEORGE M. LITTLE, OF PITTSBURGH, PENNSYLVANIA, ASSIGNOR TO WESTINGHOUSE ELECTRIC & MANUFACTURING COMPANY, A CORPORATION OF PENNSYLVANIA.

PROTECTED ELECTRODE FOR ELECTRIC FURNACES.

Application filed May 24, 1921. Serial No. 472,093.

To all whom it may concern:

Be it known that I, GEORGE M. LITTLE, a citizen of the United States, and a resident of Pittsburgh, in the county of Allegheny and State of Pennsylvania, have invented a new and useful Improvement in Protected Electrodes for Electric Furnaces, of which the following is a specification.

My invention relates to electric furnaces, and particularly to electric-resistance furnaces, and it has for its object to provide means to protect the electrode of an electric-resistance furnace against oxidation by entering air.

In my copending application, Serial No. 454,776, filed March 23, 1921, I have disclosed an electric furnace having a carbonaceous resistor, the individual elements of which are held in their operative positions relatively to each other and in the furnace by means of an elongated electrode which is resiliently pressed against the resistor.

A certain amount of oxidation of the electrode takes place in the furnace wall through which the electrode extends, and my invention has particular reference to a method for protecting the electrode at this place.

In practicing my invention, I provide a well or hopper in the furnace wall through which an electrode extends, and place therein a mass of granular carbonaceous material surrounding the electrode. The well is open to the outside, permitting of tamping the granular material tightly around the electrode and of renewing the same whenever this becomes necessary by reason of its oxidation.

In the single sheet of drawings, Figure 1 is a view, in vertical section, of an electric-resistance furnace comprising the device embodying my invention, and

Fig. 2 is a view, in section, of a portion of an electric furnace comprising a modification of the device embodying my invention.

An electric furnace 10 comprises an outer metallic casing 11 provided with suitable supporting members 12. An outer layer of heat-insulating material 13 comprises a plurality of bricks or blocks of any suitable refractory material. An inner layer 14 comprises a plurality of bricks or blocks of any suitable high-temperature resisting re-

fractory material used in electric furnace work.

The walls 14 are suitably spaced apart to provide a furnace chamber 15 of any suitable or desired contour and dimensions.

A heating member 16 is located in the chamber 15 and comprises a plurality of carbonaceous elements of the type disclosed in my hereinbefore mentioned application. The elements of the member 16 are pressed together by means of an extended carbonaceous electrode 17 which operatively engages a graphite end block or plate 18, a similar rear end plate 19 being provided in accordance with the usual practice.

A water-cooled contact terminal 20 has wedging engagement with the conically tapered end of the electrode 17 and is maintained in engagement therewith by means of resilient compressing means comprising a helical spring 21, a threaded stud 22, a nut 23 and a washer 24. The expanded end of the stud 22 presses against the contact terminal 20, an insulating member 25 being interposed therebetween. The resilient compressing means is illustrated schematically only, it being understood that any suitable compressing means may be employed. An asbestos ring 26 may be located in the outer walls and the metallic casing to prevent current leakage from the contact terminal 20.

During the operation of the furnace, the inner and outer walls may separate a slight amount by reason of their being built separately and having relatively different coefficients of expansion, and the individual bricks may also separate sufficiently to permit air to enter.

As the furnace is provided with an opening 27 to permit of the introduction and the withdrawal of metal articles, a certain amount of air will enter through this opening, and means are disclosed in the hereinbefore mentioned application for producing a sooty vapor in the chamber to protect the resistor and the electrode. The electrode is, of course, hottest at the end immediately adjacent the graphite block 18 and coolest at the outer end where the water-cooled contact terminal 20 is located. If no provision is made for protecting the electrode in the walls 13 and 14, air entering between the individual layers of bricks and flowing up

wardly between the walls 13 and 14 would strike the electrode and oxidize the same by reason of its relatively high temperature.

Means, comprising a well 28 located in the two walls 13 and 14 and extending to below the electrode 17 and to the upper end of the furnace and filled with granular carbonaceous material 29, serves to protect the electrode 17 against such entering air.

10 I may use powdered lamp-black, charcoal, granular coke or graphite, and it is to be noted that the well opening to the outside of the furnace provides means for introducing such granular carbonaceous material 15 around the electrode intermediate its length, which granular material may be tightly tamped around the electrode and is readily renewable, whenever required, by reason of the oxidation of the mass of material immediately adjacent the electrode. Such oxidation is, of course, a chemical union of the oxygen in the entering air with the carbonaceous material, and, if permitted to affect the electrode, would cause a reduction of its 25 cross section.

As the position of the electrode, where it passes through the walls 13 and 14, is not the same at all times during the operation of the furnace, by reason of unequal expansion and contraction of the various parts of the furnace, provision is made in the resilient compressing means for permitting the electrode to adjust itself to such changes of relative location.

35 It may be noted that the position of the contact terminal 20 is such that it projects into the wall 13 and that its inner end engages the granular material 29, and hence, is a means for preventing any of the material 40 29 from spilling or falling outwardly. Sufficient clearance is allowed between the wall 13 and the contact terminal 20 to permit of the relative movement hereinbefore described.

As the carbonaceous material placed in the 45 well 28 is granular, the relative movement of

the electrode 17 through the walls 13 and 14 is easily effected without in any way decreasing the efficiency of the protection provided.

In the modification illustrated in Fig. 2, the well 28 does not extend to the top of the furnace, but is open at the side of the furnace immediately above the electrode and its associated contact terminal. A suitable container 30 may be provided to retain the granular material in place in the well. The operator is thus permitted to renew or tamp the granular material from the side, instead of from the top of the furnace.

It may be noted that the device embodying my invention provides a relatively simple means surrounding the electrode for chemically uniting with an entering oxidizing fluid to protect the electrode while permitting free movement of said electrode relative to the walls and to the mass of protecting material.

Various modifications may be made in the device embodying my invention, without departing from the spirit and scope thereof, and I desire that only such limitations shall be placed thereon as are imposed by the prior art or are specifically set forth in the appended claim.

I claim as my invention:

An electric furnace comprising a plurality of furnace walls, an electrode extending horizontally through one of said walls and movable relatively thereto during operation of the furnace, a well in said wall, a quickly renewable granular oxidizable barrier in said well surrounding said electrode over a portion of its length intermediate its ends, said barrier being adapted to prevent chemical action of entering air upon said electrode but permitting free movement of said electrode relatively to said wall.

In testimony whereof, I have hereunto subscribed my name this 18th day of May, 1921.

GEORGE M. LITTLE.
